UNITED STATES PATENT OFFICE.

THOMAS J. LITTLETON, JR., AND JAMES P. TYNER, OF ESTILL SPRINGS, TENNESSEE.

COMBINATION GARMENT-KNIFE.

1,079,300.

Specification of Letters Patent.

Patented Nov. 18, 1913.

Application filed January 24, 1913. Serial No. 744,018.

To all whom it may concern:

Be it known that we, THOMAS J. LITTLETON, Jr., and JAMES P. TYNER, citizens of the United States, residing at Estill Springs, 5 in the county of Franklin and State of Tennessee, have invented new and useful Improvements in Combination Garment-Knives, of which the following is a specification.

The invention relates to a tailoring instrument, and more particularly to the class 10 of combination garment knives.

The primary object of the invention is the provision of a knife of this character in which seams in garments or the like may be 15 readily and conveniently ripped, silk, linen, cloth, or other fabrics cut, and button holes formed with ease and regularity both as to size and position.

Another object of the invention is the provision of a knife of this character which is 20 extremely simple in construction, thoroughly reliable and efficient in its purpose, and inexpensive in manufacture.

With these and other objects in view, the 25 invention consists in the construction, combination and arrangement of parts as will be hereinafter more fully described, illustrated in the accompanying drawing, and pointed out in the claim hereunto appended.

30 In the drawings:—Figure 1 is a plan view of a knife constructed in accordance with the invention, the blade being shown extended. Fig. 2 is a vertical longitudinal sectional view thereof. Fig. 3 is a view similar 35 to Fig. 1, showing the knife blade by full lines in folded or closed position, and also by dotted lines in various adjusted positions.

Similar reference characters indicate corresponding parts throughout the several 40 views in the drawing.

Referring to the drawing by numerals, the knife comprises a body 5 which may be made from a single piece or formed from a pair of sections if found desirable, and is 45 provided with a space 6 between resilient side limbs 7, the outer face at one side of the body being formed with graduations 8 providing a scale whereby measurements may be made when necessary.

Arranged within the space 6 between the 50 limbs 7 is an adjustable outwardly tapered knife blade 9 having a needle point 10 at its smaller end making its entrance into cloth or other fabric sure and easy and provided with a beveled side cutting edge 11, the blade 55 being formed with a central elongated slot 12 through which is passed a pivot screw 13, the same being engaged in the limbs 7 and has threaded thereon a binding nut 14 whereby the blade 9 can be firmly held in adjusted 60 position in the handle.

The inner or larger end of the blade 9 is formed with a segmental shaped portion 15 from which extends a projection or finger nib 16, one side of which is formed with 65 filing ribs, or is roughened, at 17, whereby when the blade 9 is folded inwardly in the handle 5 needles may be sharpened upon the said roughened surface 17 of the nib, the nib also being provided to permit the adjustment of the knife blade 9. When the blade 9 is swung outwardly into a 90 degree angle or in alinement with the handle 5 and adjusted so as to project the desired degree or distance outwardly from the said handle it 70 75 may be used to cut or punch button holes with regularity and exactness, the side or end of the handle 5 contiguous to the blade, or in other words, the free ends of the limbs 7 being designed to serve as a gage to limit 80 the penetration of the blade 9 in the fabric as may be desired. The knife is extremely useful for tailoring purposes or for dress-making uses.

From the foregoing it is thought that the 85 construction and manner of operation of the device will be clearly understood, and therefore a more extended explanation has been omitted.

What is claimed is:—

As an article of manufacture, a combination garment knife comprising a handle having a bifurcation extending partially through the same and opening through only one end thereof, the closed end of the bifurcation being formed with inwardly converging opposed abutments, an outwardly tapered knife blade arranged within the bifurcations 90 95

and having an elongated slot centrally therein, a pivot passed through the slot and fixed in the handle for guiding the knife blade in various adjusted positions, and a finger nib 5 formed at the larger end of the blade in alinement with the slot therein, the said blade being provided with a single knife edge and a point at its smaller end.

In testimony whereof we affix our signatures in presence of two witnesses.

THOS. J. LITTLETON, Jr.
JAMES P. TYNER.

Witnesses:

JAMES T. CHILTON,
W. K. DICKENS.
